ROTARY CASTING MACHINE FOR PRODUCING HOLLOW RUBBER OR LIKE ARTICLES

Dietrich G. Rempel, Akron, Ohio, assignor to Rempel Manufacturing, Inc., Akron, Ohio, a corporation of Ohio

Application December 22, 1949, Serial No. 134,512

5 Claims. (Cl. 18—26)

1

This invention relates to improved apparatus for producing articles by deposition of flowable material in sectional cavity molds.

This application is a continuation in part of application Serial No. 83,378, filed April 19, 1949 now Patent 2,569,869.

The present invention is particularly adaptable for carrying out the rotary casting process of said co-pending application, by which a plaster-of-Paris cavity mold containing a quantity of latex, or similar aqueous dispersion material, is rotated about a plurality of angularly disposed axes, to deposit the latex on the mold cavity surface portions, aided by capillary flow of water outwardly through the mold pores.

An object of the invention is to provide improved mold-rotating apparatus, particularly useful for connection with said rotary-casting process, which is operable to apply compound rotary movement to a mold or molds about a plurality of axes, with smooth, steady action thereon for attaining maximum uniformity of wall thickness in the products formed in the mold cavities.

Another object of the invention is to provide mold-rotating apparatus of the class described including improved means for applying compound rotative movement to a mold containing article-forming fluid in a manner which assures complete uniform coverage of all portions of the mold cavity surfaces, including undercut portions thereof, and particularly overhanging, difficult-to-reach wall portions which might otherwise be missed because of the fluid falling from one cavity portion to another by gravity.

Still another object of the invention is to provide mold-rotating apparatus of the character described, wherein in the inoperative condition of the same a mold-supporting unit is self-operating to be presented in convenient position for facilitating quick loading and unloading the molds therefrom.

Other objects of the invention will be manifest from the following brief description and the accompanying drawings.

Of the accompanying drawings:

Figure 1 is a side elevation, partly broken away and in section, of a rotary casting machine embodying the features of the invention.

Figure 2 is a cross-section, on the same scale, taken substantially on the line 2—2 of Figure 1.

Figure 3 is a top view of a mold stack on the machine, as viewed on the line 3—3 of Figure 1.

Figure 4 is a bottom view of part of the mold-rotating mechanism, as viewed substantially on the line 4—4 of Figure 1.

Figure 5 is a vertical cross-section taken substantially on the line 5—5 of Figure 2.

Figure 6 is a side elevation on a reduced scale, partly broken away and in section, illustrating

2

a finished hollow rubber article produced in the rotary casting machine.

Referring to Figures 1 to 5 of the drawings, there is illustrated an improved machine particularly adaptable for practicing said rotary casting method, wherein a plurality of mold-rotating units 20 are each adapted to have removably supported thereon a plurality of stacked plaster-of-Paris, sectional cavity molds 21, each said unit 20 being operable to apply a compound rotary movement to the respective stack 22.

Accordingly, supporting members or arms 23 of each of four such units 20 have hubs 23a keyed or otherwise fixed in the respective ends of two shafts 24 and 25, which are each suitably journaled in spaced, horizontally aligned bearing members 26 and 27 mounted on webs 28 and 29 extending vertically in parallel planes from a relatively fixed support 30. The shafts 24 and 25 are rotated about the parallel, horizontally extending axes thereof, as by means of a common electrical power unit 32 through endless chains 33 and 34 extended between spaced pinions 35 on the power unit and relatively larger gears 36 and 37, fixed on the shafts 24 and 25 between the spaced bearing members 26 and 27 thereof. The units 20 otherwise being similar in all respects, only one thereof will be described in detail and, therefore, like parts will be designated by like numerals.

30 The arm 23 extends from its hub portion 23a at a substantial angle to the axis of the shaft. That is, the angularly extending arm is adapted to swing in a conical path with rotation of the shaft. Journaled in suitable bearing means at 35 the outer end of arm 23 is a spindle 38 which extends freely inwardly toward intersection with the axis of shaft 24, substantially at right angles to said angle of the arm. The molds 21 are circular or disc-shaped and are centrally apertured, as indicated at 39, for free sliding reception 40 of spindle 38 therethrough, a stack 22 of such molds being adapted to be releasably clamped between a plate 40, fixed on the spindle at the inner end thereof adjacent the arm and a removable clamping plate 41 of a quickly releasable clamping device 42. Spacers 43 of relatively small size are positioned between the adjacent plaster molds of the stack to permit circulation of air for purposes to be described later. For counterbalancing the unit 20 with the molds 21 stacked thereon, a pair of parallel rods 44 extending from hub 23a, in the same general angular direction as spindle 38, have a counterweight 45 slidably adjustable along the same. The weight 45 is adjustable so that the loaded unit 20 will be substantially dynamically balanced for smooth rotative operation thereof, but at the same time so that when the machine is in stopped position the unit will always turn to the position

55 thereof shown in Figures 1 and 2, that is, with the

spindle extended upwardly and forwardly, for ease of loading and unloading the molds therefrom. With a stack of five molds as shown, the center thereof will be substantially aligned with the axis of shaft 24 (or 25) although more or less molds may be readily balanced in the unit by adjustment of the counterweight 45.

Improved means is provided for steady, effective and efficient rotation of spindle 38 about its axis in synchronism with rotation of the unit about the axis of shaft 24 (or 25), for attaining uniform deposition of article-forming material in the mold cavities. Accordingly, a fabric-reinforced, flexible rubber V-belt 47 is engageable between a tapered annular groove 48 of a relatively fixed sheave 49, formed integral with an outward extension 26a of bearing 26 (or 27), and a tapered annular groove 50 of a sheave 51 rotatably mounted on a stem 52 projecting from the arm 23, at the outwardly presented side thereof opposite to the spindle 38. For guiding or bending the belt 47 to have the opposite looped ends thereof in angularly disposed planes of the fixed and rotatable sheaves 49 and 51, respectively, idler pulleys 52 and 53 are suitably adjustably mounted at opposite sides of arm 23 at the juncture of said two planes. The spindle 38 is adapted to be rotated on its axis, by means of a gear 54 fixed on a reduced extension 55 of the spindle, meshing with a suitable gear 56 concentrically attached to the sheave 51. In other words, if the belt 47 were connected directly to a gear (not shown) on the spindle, the latter would be driven in the same direction as the arm, and the rotative movement of the molds with the spindle would be negatived. A suggested speed reduction between the spindle 38 and shaft 24, is approximately one revolution per minute of arm 23 about the axis of shaft 24 (or 25), to one and one quarter revolutions per minute of the spindle 38. In other words, when the arm 23 is rotated with shaft 24, rotative action is transmitted to sheave 51 by the belt 47, steadily progressively "walking" around said fixed sheave 49.

The clamping device 42 includes a nut 58 threaded on an externally threaded boss 59, said boss having a central bore through which the spindle 38 is slidably receivable. A handle 60 on nut 58 is operable to turn the same on the threaded boss 59, axially outwardly against a split collar 61 releasably fixed on the spindle, thereby to urge the plate 41 inwardly to apply requisite clamping action to the mold stack against said plate or member 40 attached to the spindle. The split collar 61 has the spindle 38 slidably received through a central aperture thereof, and is releasably clamped in fixed relation to the spindle by operation of a handle 62 suitably mounted and provided with cam or equivalent means to urge opposite sides of the split portion of the collar together. As a safety feature, to prevent accidental removal of the clamping device 42 and molds 21 from the spindle, a freely projecting end portion of spindle 38 is provided with an annular groove 64 for reception of opposed prongs of an elongated U-shaped spring clip 65 somewhat like a hairpin. (See Figures 1 and 3.)

In order to assure that the latex will reach cavity surfaces adjacent overhanging parts of the mold defining adjoining deeply recessed portions of each article-forming cavity, a suitable mechanism 66 is provided for automatically reversing the direction of operation of power unit 32. This may include, for example, a cam 67

which is progressively engaged and moved by a finger 68 carried by one of the chains 33, to operate a reversing switch (not shown) after a number of revolutions of shaft 24 in either direction.

5 In use of the mold-rotating apparatus, described above, loading and unloading of the molds 21 is accomplished while the mold-rotating units 20 are in the inoperative position best shown in Figure 1, and with the safety clip 64 and clamping device 42 removed from spindle 38. For this purpose the clamping device is quickly removable by first moving handle 62 to release the cam pressure thereof on split collar 61, which is then slipped off the end of the spindle. This 10 permits removal of the plate 41 with nut 58 thereon from the spindle. The molds 21 with articles formed therein by a previous mold-rotating cycle, are similarly removable one at a time, and then replaced by molds having predetermined quantities of flowable material, such as latex, in each article-forming cavity thereof, in the same stacked relation. The new stack 22 of molds is clamped against relatively fixed plate 40, by application of plate 41 and collar 61 to the 15 spindle, as shown in Figure 1, turning the handle 62 to clamp the collar fixedly on the spindle, and operating the handle 60 to back the nut 58 on threaded boss 59 against the collar. When the mold stacks of all units 20 are thus clamped 20 therein the power unit 32 is started to rotate the shafts 24 and 25, thereby swinging the arms 23 in conical paths of movement thereof and causing the spindles to rotate on the axes of the same.

The resultant simultaneous rotation of the 25 molds about angularly disposed axes in said periodically reversing directions, for approximately forty-five minutes, is effective to deposit the latex bodies on the mold cavity surfaces in accreted 30 layerings, crossing and recrossing in diverse directions of flow of the latex, until all of the latex 35 has been so deposited in the shape of a hollow character animal A as shown in Figure 6, for example, of substantially accurately uniform wall thickness. It will be noted that the molds are 40 not only rotated about the axes of shafts 24 (or 25) and spindle 38, but due to movement of arm 23 in a conical path there is a resultant tilting of the molds above and below pivot points on the axes of said shafts 24 and 25, that is, between 45 the angle of the molds as shown in Figure 1 and an extreme opposite angular position thereof when the arm 23 is in a topmost position of rotation (not shown). Compound rotative movement of the mold stacks about a multiplicity of 50 axes for complete uniform coverage of the mold 55 cavities is further assured by automatic operation of the reversing mechanism 66.

The time required to complete the compound 60 rotational step may vary according to conditions, such as differences in the characteristics of the deposition material, desired thickness and size of the completed article, etc., but in actual full scale production of rubber toys of one type (see Figure 6) by the present method it has been found 65 that latex deposition to full thickness may be accomplished in approximately forty-five minutes.

The mold-rotating machine may be completely 70 enclosed by a housing H (see Figures 1 and 2) within which heated air from a suitable source (not shown) is circulated around the mold stacks 22, and between the porous molds thereof, to maintain the capillary movement of water from the latex in the respective mold cavities continuously outward through the mold pores, at all times 75 while there is either liquid or deposited latex

in the molds. A suitable temperature for this air is for the present purposes approximately 90° F.

This moderately heated air, then, in circulating around the molds, including the spaces between adjacent molds, all during the pre-drying stage, will maintain the molds relatively drier on the outside than on the inside (from the cavity surfaces), and as long as there is water in the latex deposits such water will be steadily dissipated outwardly by capillary attraction and evaporation and no wet layers or strata will be created to cause formation of recesses and holes in the articles. When succeeding latex supplies are placed in the molds the molds will again be desirably wetter inside than out and the capillary movement of the water will be maintained continuously or at least consistently outwardly as long as there is water in the latex or latex deposits.

When each article is fully formed, by deposition or accretion of latex within its mold cavity, and is ready for removal from the molds, substantially all water from the initial predetermined quantity of latex will have passed outwardly of the mold cavity by capillary attraction, through a myriad of pores in the mold material, the water being dissipated at the outer mold surfaces by evaporation.

After the articles have been fully formed and pre-dried in the mold-rotating machine, as described above, the stacks are removed therefrom and the individual molds are opened for removal of the articles A. These articles, which may each have a relatively small whistle aperture 68 provided in the wall thereof, either during or after the rotary-casting cycle described above, are then placed on racks and vulcanized in known manner in open heat. The whistle apertures prevent the air within the articles from expanding or contracting to an extent which would cause the same to rupture or to collapse, respectively.

Although the improved apparatus has been described particularly in connection with the production of hollow rubber articles, it may be similarly utilized in the manufacture of hollow articles from other materials which are capable of flowing and drying or setting substantially in the manner described.

Modifications of the invention may be resorted to without departing from the spirit of the invention or the scope of the appended claims.

What is claimed is:

1. A machine for producing hollow articles by distribution of flowable material in article forming cavity molds comprising a support, a shaft rotatable on said support, a mold carrying arm extending radially at an angle to the axis of said shaft and rotatable therewith, a mold-supporting member mounted on said arm to rotate about an axis extending angularly of the arm and intersecting said shaft axis at an angle thereto, means for mounting at least one mold on said mold-supporting member, means for simultaneously rotating said shaft and said mold-supporting member, said mold mounting means including a spindle extending therefrom for reception through apertures in the molds, a releasable clamping device for removably retaining at least one mold on the spindle, a counterweight carrying rod fixed to said mold carrying arm and extending radially from the axis of said shaft opposite said mold-supporting member and substantially parallel with said mold carrying spindle, and a counterweight carried by

and movable to adjusted positions along said rod for adjustably counterweighting the molds on said mold carrying spindle.

2. A machine for producing hollow articles by distribution of flowable material in an article-forming cavity mold, comprising a support, a shaft rotatable on said support, a mold-carrying arm extending at an angle to the axis of said shaft and rotatable therewith, a mold-supporting member mounted on said arm to rotate about an axis angularly of the arm and intersecting said shaft axis at an angle thereto, means for mounting at least one said mold on said mold-supporting member, and means for simultaneously rotating said shaft and said mold-supporting member, said simultaneously rotating means including an annular transmission member rotatable on said arm, an annular transmission member relatively fixed on said support concentrically with said shaft axis, a continuous flexible transmission element in driving engagement with both said rotatable and said relatively fixed transmission members, guide means on said mold-carrying element intermediate said fixed and rotatable transmission members for guiding said flexible transmission element substantially in angularly disposed planes of said fixed and rotatable transmission members, means connecting said rotatable transmission member to rotate said mold-supporting member, and means to rotate said shaft and thereby through resulting progressive walking action of said flexible transmission element on said relatively fixed transmission member to rotate said rotatable transmission member.

3. A machine as set forth in claim 2, said mold mounting means including a spindle extending freely therefrom for reception through an aperture in said mold, and a releasable clamping device for removably retaining at least one said mold on the spindle.

4. A machine as set forth in claim 3, said rotatable and fixed transmission members having an annular tapered grooves and said flexible transmission element being a reinforced rubber V-belt engageable therein.

5. A machine as set forth in claim 1, said clamping device including a plate fixed on the spindle for backing said mold or molds received on said spindle, a removable plate slidably mounted on the outer end of said spindle, a split nut slidably received on said spindle outwardly of said plate, means for contracting said split nut to fix the same on the spindle, a threaded boss on said clamping plate projecting toward said split nut, and a nut threaded on said boss and rotatable thereon against said fixed split nut to urge said slidable plate into clamping engagement with said mold or molds.

DIETRICH G. REMPEL.
